STOVE

Edwin Esson, Kansas City, Mo., assignor to Locke
Stove Company, Kansas City, Mo., a corpora-
tion of Missouri

Application November 18, 1942, Serial No. 466,012

9 Claims. (Cl. 126—68)

1

This invention relates to heating stoves and particularly those of the magazine type for burning solid fuels.

Usually the radiating surfaces of radiant heating stoves become so intensely heated that it is impractical to provide them with porcelain or enameled exteriors. Consequently radiant heating stoves are unsightly in appearance and do not present the modern exteriors of the present day circulating heaters wherein the heating unit is enclosed in a casing that may be finished in any desired manner. Circulating heaters are therefore more desirable for their appearance but they are more expensive than radiant heaters and in many homes, particularly those not so well constructed, radiant heaters are more efficient and give better service.

It is, therefore, a principal object of the present invention to provide a radiant heater of relatively simple, inexpensive construction and having the pleasing appearance of a circulating heater.

A further object of the invention is to provide a radiant heater with an air circulating section whereby the stove is in part a circulating heater.

Other objects of the invention are to provide a stove construction wherein the radiating surfaces are maintained at sufficiently low temperature to permit the use of porcelain or enamel exteriors; to provide a stove structure having a minimum of cast parts; to provide a stove structure wherein the parts are readily assembled; to provide a radiant heating stove wherein the upper portion acts in the manner of a circulating heater to dissipate the top heat; and to provide the cast parts of the stove with simple shapes so that they may be readily molded.

In accomplishing these and other objects of the invention, I have provided improved details of structure, the preferred form of which is illustrated in the accompanying drawings, wherein:

Fig. 1 is a perspective view of a heating stove constructed in accordance with the present invention.

Fig. 2 is a vertical section through the heating stove on the line 2—2 of Fig. 1.

Fig. 3 is a vertical section through the heating stove on the line 3—3; Fig. 2.

Fig. 4 is a horizontal section through the heating stove on the line 4—4 of Fig. 3.

Fig. 5 is a fragmentary perspective view of an interior portion of the stove particularly illustrating the key tiles of the refractory lining.

Fig. 6 is a perspective view of one of the flue refractories used in cooperation with interme-

2

diate refractories for lining the magazine chamber.

Fig. 7 is a detail perspective view of some of the metal parts of the stove shown in spaced relation to better illustrate the construction thereof.

Fig. 8 is an enlarged sectional view through a portion of the sheet metal body illustrating the porcelain exterior thereof.

Referring more in detail to the drawings:

1 designates a heating stove constructed in accordance with the present invention and which includes a shell 2 composed of a base section 3, a body section 4 and a top section 5 all preferably formed of sheet metal and cooperating with cast sections hereinafter described. The body section 4 is of the wrap-around type in that it is formed of a metal sheet shaped to provide a front 6, sides 7 and a back 8, the edges of the sheet being connected together to form a seam 9 preferably in the center of the back 8 as shown in Figs. 4 and 6. The lower edges of the sheet are preferably bent outwardly and downwardly to provide a perimetric bead or trim 10 and then inwardly to provide a flange 11 having openings 12. The upper edges of the sheet are bent inwardly to provide flanges 13 having similar openings 14. The corners of the body section are preferably rounded and the front, back and sides 30 are bulged outwardly throughout the height thereof to facilitate expansion and contraction thereof during heating and cooling and to avoid noise and crazing of the finish applied thereto.

The front 6 has a cut-out 15 at the bottom thereof to accommodate an ash compartment door frame 16 that is secured to the marginal edges of the opening and carries a door 17 hinged thereto along the lower edge as at 18, the door having a draft damper 19 manipulated by a handle 20. The upper portion of the front has air inlet openings 21 located at the respective ends of a slot 22, which slot slidably mounts a damper 23 for selectively closing the openings 21.

The base 3 conforms in shape to the body section and has upper and lower inwardly directed flanges 24 and 25 for respectively seating the flanges 11 and mounting the base upon a floor or suitable support. The base has perimetric beads 26 formed on the respective sides of ventilating openings 27. The body portion is attached to the base by fastening devices 28 extending through the openings 12 and through corresponding openings in the upper flange of the base.

Seated on the flanges 13 is a frame 29 including a web 30 having a depending outer rib 31 en-

gaging over the upper edges of the front, rear and side walls to assist in retaining the shape of the body section. The frame 29 also has an upwardly extending marginal rib 32 which cooperates with the lower rib 31 in forming an encircling trim or band 33 corresponding to the trim 10 at the lower portion of the body section. The inner edge of the frame has an upwardly extending flange 34, the front portion 35 thereof being of slightly greater height to form the lower edge of a door frame, later described. The frame 29 is preferably formed in front and back sections to facilitate casting although it may consist of a single member.

Seated upon the web 30 is a dome 36, having sides 37 and 38 and a back 39 carrying foot flanges 40 engaging over the adjacent portions of the flange 34 and which are secured to the web 30 by fastening devices such as bolts 41. The dome also includes a downwardly and rearwardly sloping top 42 rounding into the side and back walls as at 43. The front of the dome comprises sides 44 and a top rail 45 which cooperate with the flange 35 to complete the door frame previously mentioned and which is provided with openings 46 therein. Formed in the back 39 is a notch 47 shaped to accommodate the lower section 48 of a flue outlet 49, the upper part 50 of which is carried by the back 39 of the dome. The part 48 has a plate portion 51 filling the notch 47 and is provided with a flange 52 forming a continuation of the flange 40 when the parts are assembled. The lower section 48 also includes a substantially semicylindrical extension 53 which cooperates with the part 50 to form a collar extending beyond the plane of the rear wall 8 to connect a smoke pipe 54.

Fixed to the sides 44 of the door frame are flanges 55 on forwardly extending wings 56, the front edges of which substantially register with the upwardly extended plane of the front wall 6 and have outwardly extending flanges 57 rounding into top flanges to provide a trim at the sides of the door opening and to attach sheet metal side members 59 of the top section 5 previously mentioned. The lower edges of the wings have notches 62 which cooperate with notches 63 in lugs 64 carried on the front web portion 30 of the frame 29 so as to provide journals mounting trunnions 65 extending laterally from the lower edge of a door 66, the door 66 being arranged to seat against the frame of the dome as shown in Fig. 1. The sides of the door have inwardly extending wings 67 to form guards for preventing spilling of fuel from the door when the stove is being charged with fuel as later described. The lower ends of the wings terminate in hooked portions 68 which engage the flange 35 to limit opening movement of the door as shown in Fig. 2. The door is provided with a suitable handle 69 to facilitate opening and closing thereof.

The side members 59 are preferably formed of pressed metal and have wall portions 70 forming upward continuations of the sides 7 and the front, rear and top marginal edges thereof round inwardly and terminate in inwardly extending flanges 71. The lower edges of the members 59 have inwardly extending flanges 72 to seat upon the outer portion of the web 30 of the frame, the side members 59 and frame 29 being attached to the flanges of the body section by fastening devices 73 extending through openings 74 of the flanges 72, openings 75 in the web 30 and the openings 14 in the flange 13 previously mentioned. In order to connect the trim of the wings 56 with

the inwardly extending flanges of the side members 59, the trim is provided with laterally extending pins 76 which project into openings 77 in the flange 71.

Bridging the space between the side members 59 and spaced above the top 42 of the dome 36 is a sheet metal grill 78 having depending flanges 79 and 80 on the marginal front and sides thereof. The front flange 79 abuts against the rail 45 and is secured thereto by fastening devices 81. The side flanges 80 abut against the upper in-turned flanges of the side members 59 and are similarly secured by fastening devices 82. The central portion of the grill is preferably ribbed as at 83 to stiffen the structure and form a decorative trim. Formed in the top at the respective sides of the rib are slot-like air outlet openings 84 which cooperate with similar slots 85 in the side members 59 for the circulation of air to be heated, as later described. The back portion of the top section 5 is closed by a downward extension 86 of the grill top and which has a notched lower edge 87 fitting over the flue connection previously described. The sides of the extension 86 are flanged inwardly to abut against the in-turned rear flanges of the side members, these flanges being secured by fastening devices similar to the other flanges. The lower edge at the respective sides of the notch 87 are also flanged to seat upon the rear web portion of the frame 29 and be secured thereto by suitable fastening devices. The side members 59 and grill section thus cooperate with the dome and frame 29 in forming an air passageway around the heated surfaces of the dome so that air moving through the slots 85 and openings 88 in the part 86 is heated by contact with the hot surfaces of the dome and discharged through the slot-like openings 84 of the grill portion, thereby providing a circulating section for the heater.

The damper previously mentioned is best shown in Fig. 7 and includes a plate 89 slidable against the front 6 and which has openings 90 in the ends thereof to register with openings 21 previously mentioned, the plate being secured to the front 6 by a suitable fastening device 91 extending through the slot 22. Extending forwardly and downwardly from the plate is an arm 92 by which the damper may be manipulated. In order to improve the appearance and cover the damper, the frame 29 has a shield portion 93 extending downwardly and outwardly over the damper in spaced relation therewith so as to provide air inlet to the damper openings.

Supported on the flange 11 is a plate 94 forming the bottom of the ash compartment and which has upwardly directed marginal flanges 95 seating within the groove formed by the trim 10. Mounted in the ash compartment and supported on the bottom 94 is the usual ash receptacle 96.

Positioned within the body section and supported from the bottom 94 by corner legs 97 is an outer grate member 98 having an imperforate marginal portion 99 forming a ledge for supporting refractories later described. The intermediate portion of the grate ring has the usual slot-like openings 100 and is provided with a central opening 101 to accommodate a shaker grate 102 seated upon a flange 103 encircling the opening 101 as best shown in Fig. 3.

Mounted within the corners of the body section are flue tiles 104 comprising superimposed blocks. The flue tiles are best illustrated in Fig. 6 and are shown as comprising wall portions 105 and 106 closely fitting within the curvature of

the adjacent walls of the body section, and protect the body section from contact with flames resulting in the flues as later described. The walls 105 and 106 connect with diagonal walls 107 by end walls 108 and 109. The diagonal walls 107 have notches 110 in the upper edges thereof which cooperate with similar notches in the lower edges of an upper tile to form openings 111 through which gases evolved incidental to coking of fuel are discharged into the flue ducts 112 that are provided within the interior of the flue tiles. The tiles are of a size so that they extend substantially to the top of the body portion and the outlet ends of the flue ducts are in direct communication with the interior of the dome.

Interposed between the flue ducts are refractory lining blocks 113 which cooperate with the diagonal walls 107 of the flue tiles to form a fuel magazine 114 above the grate. The refractories 113 are of sufficient thickness to protect the metal of the side walls of the body section. With this construction the exterior surfaces of the heater may be provided with a finish such as baked enamel, porcelain 115 or the like, since the refractories absorb and distribute the heat generated by the burning fuel and avoid hot spots which ordinarily tend to craze enamel or porcelain finishes.

The refractories are of a size to be inserted into position through the door opening. The side and rear refractories are inserted first and followed by the front refractories, the upper of which is slightly shorter and split, as at 116, Fig. 5, to facilitate placement and removal thereof when it is necessary to replace any of the tiles.

In using the heater constructed and assembled as described, the door 66 is opening and a fire kindled upon the grate. A sufficient amount of fuel is inserted through the door opening to fill the magazine 114. The draft damper 19 is opened so that sufficient air is admitted to the ash compartment for upward flow through the grate and into the refractory flues by way of the openings responsive to draft effected by the chimney to which the stove is connected. The fire burns upwardly and inwardly of the magazine and the burning fuel settles downwardly so that the ashes are discharged through the grate into the ash pan 96. Burning of the fuel in the lower portion of the magazine results in coking of the fuel in the upper portion and discharge of gases therefrom, which gases are passed through the openings of the flue tiles and burned therein, the spent gases being discharged from the upper ends of the flue into the dome and through the dome to the flue outlet. Owing to the fact that the flue is in effect partially insulated from the side portions of the shell, the shell is maintained at sufficient low temperature to prevent injury to the exterior finish thereof. The refractories also provide more efficient and uniform distribution of the heat to the radiating surfaces, thereby avoiding hot spots that are ordinarily characteristic of the magazine type stove. The spaces formed over the dome portion of the combustion chamber provide for circulation of air through the slot-like openings at the front and rear of the casing to carry away the top heat, thereby providing in part a circulating heater while the walls, front, and rear side members act as heat radiating surfaces to heat the surrounding air.

From the foregoing it is obvious that I have provided a radiant type stove of simple, inexpensive construction and which is designed in the manner that the exterior surfaces are main-

tained at sufficiently low temperature to permit enameling or porcelainizing, thereby providing a radiant heater having all the desirable appearances of the more expensive full circulating type of heater.

What I claim and desire to secure by Letters Patent is:

1. In a heater of the character described, a sheet metal body section forming radiant heat transmitting portions, a refractory lining facing the inner surfaces of the section in covering relation with said heat transmitting portions for forming a fuel magazine therein, a cast metal frame supported on the body section, a cast metal dome carried by the frame for closing the top of the magazine, sheet metal sections supported on the frame and forming upward continuations of said body section and having air inlet openings, and a sheet metal top cooperating with said last named sections to enclose said dome and having air outlet openings for circulation of air around said dome.
2. In a heater, a wrap-around sheet metal body having front, rear and side walls, a grate supported in upwardly inset relation from lower edges of said sheet to provide an ash compartment below said grate having walls formed by said sheet, flue tiles disposed within corners formed by adjacent walls and having refractory portions in heat conducting relation with said walls for distributing heat generated within the flues to said walls, refractory liners disposed between said flues and cooperating therewith to form a fuel magazine above the grate, said flues having openings connected with the magazine, a cast metal frame supported upon said body section and having a depending marginal rib engaging over the upper edge of said wrap around sheet to cooperate with the grate in maintaining rigidity of said body, a cast metal dome carried by the frame and closing the top of the magazine, a flue connection for said dome, and sheet metal members enclosing the dome in spaced relation therewith to form a passageway around said dome for the circulation of air to be heated, said sheet metal members forming upward continuations of the wrap around sheet.
3. In a heater, a wrap-around sheet metal body forming front, rear and side walls, a grate supported in upwardly inset relation from lower edges of said sheet to provide an ash compartment below said grate having walls formed by said sheet, flue tiles disposed within corners formed by adjacent walls and having refractory portions in heat conducting relation with said walls for distributing heat generated within the flues to said walls, refractory liners disposed between said flues and cooperating therewith to form a fuel magazine above the grate, said flues having openings connected with the magazine, a cast metal frame supported upon said body section and having a portion engaging over the upper edge of the wrap around sheet to cooperate with the grate in maintaining shape of said body, a cast metal dome carried by the frame and closing the top of the magazine, a flue connection for said dome, apertured sheet metal sections forming upward continuations of said side and rear walls, and a grill top connecting said sheet metal sections to enclose said dome.
4. In a heater, a wrap-around sheet metal body forming front, rear and side walls, a grate supported in the lower portion of said body, flue tiles disposed within corners formed by adjacent walls and having refractory portions in heat

conducting relation with said walls for distributing heat generated within the flues to said walls, refractory liners disposed between said flues and cooperating therewith to form a fuel magazine above the grate, said flues having openings connected with the magazine, a frame supported upon said body section, a dome carried by the frame and closing the top of the magazine, a flue connection for said dome, means enclosing the dome in spaced relation therewith to form a passageway around said dome for the circulation of air to be heated, said dome having an upwardly and rearwardly inclined front provided with a door frame, wings fixed to sides of the door frame and connected with said dome enclosing means, and a door for said frame.

5. In a heater, a wrap-around sheet metal body forming front, rear and side walls, a grate supported in the lower portion of said body, flue tiles disposed within corners formed by adjacent walls and having refractory portions in heat conducting relation with said walls for distributing heat generated within the flues to said walls, refractory liners disposed between said flues and cooperating therewith to form a fuel magazine above the grate, said flues having openings connected with the magazine, a frame supported upon said body section, a dome carried by the frame and closing the top of the magazine, a flue connection for said dome, means enclosing the dome in spaced relation therewith to form a passageway around said dome for the circulation of air to be heated, said dome having an upwardly and rearwardly inclined front provided with a door frame, wings fixed to sides of the door frame and connected with said dome enclosing means, a door for said frame, cooperating bearing portions in said wings and on said frame forming journals, and trunnions on the lower side edges of the door having support in said journals.

6. A heater including a body having front, rear, and side walls, a frame supported on said body and having a marginal portion engaging upper ends of said walls, a dome on said frame covering the upper end of said body and having a fuel insert opening above the front wall of said body, an upwardly and rearwardly inclined frame for said fuel insert opening, wings extending forwardly from the sides of said inclined frame and having front portions substantially registering with the front wall, a door positioned between said wings and cooperating with the inclined frame for closing said fuel insert opening, side members forming upward extensions of the side walls and spaced from adjacent sides of the dome to provide air passageways therebetween, and a top member extending between the side members to form a passageway over the top of the dome, said members having openings for circulation of air through said passageways.

7. A heater including a body having front, rear, and side walls, a frame supported on said body and having a marginal portion engaging upper ends of said walls, a dome on said frame covering the upper end of said body and having a fuel insert opening above the front wall of said body and a flue outlet connection at the rear side of said body, an upwardly and rearwardly inclined frame for said fuel insert opening, wings extending forwardly from the sides of said opening and having front portions substantially registering with the front wall, a door positioned between said wings and cooperating with the in-

clined frame for closing said fuel insert opening, side members forming upward extensions of the side walls and spaced from adjacent sides of the dome to provide air passageways therebetween, a top member extending between the side members to form a passageway over the top of the dome, and having a part forming an upward continuation of the rear wall and having an opening to pass the flue outlet connection, said member having openings for circulation of air through said passageways.

8. A heater including a sheet metal body having front, rear, and side walls, a grate supported in upwardly inset relation from the lower edges of said walls a distance to provide an ash compartment within said walls below the grate, said grate having marginal portions engaging said walls, flue tiles disposed within said body above the grate and having refractory portions for distributing heat generated within the flues to said walls, refractory liners disposed between the flues and cooperating therewith to form a fuel magazine above the grate, said flues having openings for inlet of gases evolved in the magazine and having outlets at their upper ends for products of combustion, a frame supported on the body section and having a marginal portion engaging upper ends of said walls, a dome carried by the frame and covering the top of the magazine, a flue connection for said dome, means covering the dome and having portions forming upward continuations of the side and rear walls and spaced from said dome to provide passageways for circulation of air to be heated, a door in the front of the dome, and means closing the bottom of the ash compartment.

9. A heater including a sheet metal body having front, rear, and side walls, a grate supported in upwardly inset relation from the lower edges of said walls a distance to provide an ash compartment within said walls below the grate, said grate having marginal portions engaging said walls, flue tiles disposed within said body above the grate and having refractory portions for distributing heat generated within the flues to said walls, refractory liners disposed between the flues and cooperating therewith to form a fuel magazine above the grate, said flues having openings for inlet of gases evolved in the magazine and having outlets at their upper ends for products of combustion, a frame supported on the body section and having a marginal portion engaging upper ends of said walls, a dome carried by the frame and covering the top of the magazine and having a fuel insert opening above the front wall of said body, a flue connection for said dome, an upwardly and rearwardly inclined frame for said fuel insert opening, wings extending forwardly from the sides of said opening and having front portions substantially registering with the front wall, a door positioned between said wings and cooperating with the inclined frame for closing the fuel insert opening, side members forming upward continuations of the side walls and spaced from adjacent sides of the dome to provide air passageways therebetween, and a top member extending between the side members to form a passageway over the top of the dome and having a part forming an upper continuation of the rear wall, said part having an opening for said flue connection.
